UNITED STATES PATENT OFFICE.

PAUL KARL WAGNER, OF BERLIN, GERMANY, ASSIGNOR TO STANDARD WALL PAPER COMPANY, OF HUDSON FALLS, NEW YORK, A CORPORATION OF NEW YORK.

DESIGN FOR WALL PAPER.

Application filed June 17, 1922. Serial No. 2,718. Term of patent 7 years.

To all whom it may concern:

Be it known that I, PAUL KARL WAGNER, a citizen of Germany, and a resident of Berlin, Germany, have invented a new, original, and ornamental Design for Wall Paper, of which the following is a specification, reference being had to the accompanying drawing, in which

The figure is a plan view of a section of wall paper embodying the design.

I claim:

The ornamental design for a wall paper, as shown.

PAUL KARL WAGNER.
